UNITED STATES PATENT OFFICE.

KURT VOLZ, OF HEIDELBERG, GERMANY.

GAS MIXER FOR INTERNAL-COMBUSTION ENGINES.

Application filed June 8, 1921. Serial No. 475,992.

To all whom it may concern:

Be it known that I, KURT VOLZ, a citizen of the German Republic, residing at Heidelberg, Germany, have invented certain new and useful Improvements in Gas Mixers for Internal-Combustion Engines, of which the following is a specification.

This invention relates to a device for regulating the admission of the additional air to the gas or primary mixture for internal combustion engines with the aid of a distributor rotated by the suction draft of the motor. The novelty consists essentially in the use of a large atomizer held in its position in a manner known per se by the action of a spring, said atomizer rotating in an enlarged chamber and uncovering a row of air holes for the admission of the additional air which are arranged in a circle for instance under the periphery of the atomizer, the admission of the primary mixture being controlled by an obturating body in the inner gas supply tube raised together with the atomizer.

The advantage of the invention in comparison with the devices of known construction for the regulation of the air inlet with screw wings or piston-like slides consists in the easier and undisturbed working of the distributor, in the better distribution of the air and in the improved admixing of the gas mixture and the additional air so that a thorough atomizing is effected.

In order to make the invention clearly understood, I shall proceed to describe the same with reference to several forms of construction shown by way of example in the accompanying drawings, wherein:—

Figs. 1 and 2 are two sections standing perpendicular the one to the other and showing an atomizer of simple construction.

Fig. 1^a shows in part section a modified view of the air inlet holes.

Fig. 3 is a corresponding plan view, the cap being removed.

Fig. 4 is a view similar to Fig. 1 of an atomizer with throttling element.

Figs. 5 to 7 show in longitudinal section, side elevation and plan view respectively an atomizer with lateral conduit for the gaseous mixture.

Figs. 8 and 9 illustrate the application of the atomizer shown by Figs. 5-7.

Figures 10 and 11 show a modified form of construction of the blades of the atomizer in plan view and cross section respectively.

Referring to Figs. 1-6 the casing consists of the cup-shaped under part *a* with lower tubular extension and of cap *b* enlarged at its lower end in the plane of the atomizer and which terminates in a tube and is fixed upon the part *a* with its large end. In the enlarged hollow space of the casing *a*, *b* the rotating atomizer *c* is mounted. It rotates lightly upon the axle *d* between convenient adjustable bearings *e*, *e*¹. The axle can move up and down in collar bearings *g*¹, *g*² fixed upon *a* by means of bow-shaped holders at *h*¹, *h*², *h*³. At its lowest position, the position of rest, the axle *d* is held by a spring *m* whose tension can be regulated by means of nut *n* and counter nut *n*¹. The auxiliary air flows into the casing through apertures *i*¹-*i*² in the cup-shaped part of socket *a*, the number of holes being varied according to requirement. The air enters thus into the part of the casing in which the most intense action of the atomizer takes place. An adjusting ring *k* arranged upon the inner wall of the socket over the air inlets *i* is connected with the axle *d* of the atomizer by arms *l*. Instead of simply covering the inlets *i* by the ring this ring *k* can engage with conical studs *k*¹ (Fig. 1^a) in the air holes *i* so that, if it is being raised, it gives the holes free only gradually. The stronger the suction of the engine becomes, the more will the studs be raised out of the holes *i* and the more will the cross section be enlarged for the passage of the air, so that a very fine adjusting of the air inflow is ensured. The regulating ring *e* is drawn, owing to the increased draught and rotation of the atomizer, along in the direction of the arrow *o* (Figs. 1 and 4) when the axle *d* goes upward and consequently lifted off the inlets *i* so that more air can flow in. In order to intercept drops which should flow back the air inlets *i* are raised above the inner surface of the wall of the casing. A fixed regulating ring *p* is arranged upon the outer surface of the cup-shaped part of socket *a* which is designed to effect a coarse regulation of the air admission according to the season or to the kind of fuel which is used. The holes in this ring *p* register with the air inlets *i*¹-*i*³ or not according to the position of the ring. The ring *p* is guided by means of centric slots upon screw pins *y*¹, *y*², *y*³ and it can be fixed in its position by these screw pins. The admission of auxiliary air can be shut off completely by this ring *p*.

Two peep holes r , r' are arranged the one opposite the other in the enlarged extension b upon the flatter part of the same in such a manner that the light rays from one 5 peep hole are reflected upon the other peep hole so that the observer can see clearly the mixture which flows through the apparatus. The tubular socket a has a threaded part s and the cap b has a threaded part t so that 10 they are screwed on the joining parts of the armature. The socket a and the cap b are pulled tightly against one another by the screws x^1 to x^6 so that the two parts can be easily separated for cleaning and repair. 15 A throttling ring β arranged in the tubular part of socket a (Figs. 4 to 9) is tapered towards the upper end so that, the cross section increases from the lowest throttling point. A throttling element α fixed to 20 the front part d of the axle of the blade wheel, is located with play in the throttling ring β so that the passage is more or less throttled according to whether under-pressure or over-pressure exists in the section 25 pipe. The raising and lowering of the throttling body is caused by the movement of the blade wheel c in vertical direction, this blade wheel being raised or lowered according to whether, owing to a stronger or 30 weaker suction in the suction pipe, said blade wheel revolves more slowly or rapidly so that it is raised more or less against the action of the spring, the throttling body α being drawn along. 35 The form of construction shown by Figs. 5-9 corresponds with that shown in Fig. 4, the upper bearing g^1 of the blade wheel c being however adjustably mounted in the cover b^1 , the lower bearing g^2 being stationary in the part a of the casing. Within 40 the plane of the blade wheel, preferably not below the same, tubular outlets b^2 are arranged standing at right angles to the gas inlet so that the current of explosive mixture 45 is deflected at a right angle over the blade wheel and forced practically to flow obliquely through the blades whereupon results an extraordinarily good mixing effect. The cover is hollow and can be connected 50 with a heating conduit in order that preliminary heating of the mixture be effected. In order to increase the mixing effect of the distributor or atomizer e the blades c can have apertures c^1 , the axes I—I (Figs. 10 55 and 11) of the same being arranged in a direction opposite the direction in which the gas flows (arrow c^2). The lower edges c^3 of the blades and of the holes c^1 are roughened, which can be done for instance 60 by means of a purposely thick burr and which serves to increase the tearing asunder of the gas mixture and the formation of eddies in the same which is already effected with the aid of the edges of the ring h and 65 of the air holes z . A specially good mixing

action of the blade wheel c is thus ensured.

I claim:

1. A rotating air inlet and gas mixture regulator for internal combustion engines comprising in combination with the suction pipe of the motor being enlarged at a determined part and having air inlet holes in this enlarged part, a blade wheel arranged so that it revolves above said air inlets, the axle of said blade wheel mounted so that it can move in vertical direction, an adjusting ring upon said air inlets, conical studs downwardly projecting from the lower surface of said adjusting ring and engaging with said air inlets, means for connecting said adjusting ring with said axle of the blade wheel so that said ring is lifted off said air inlets according to the movement of said blade wheel.

2. A rotating air inlet and gas mixture regulator for internal combustion engines comprising in combination with a rotating body raised by the suction draft of the motor against the action of a spring, a casting having an enlargement in the plane of the rotating body in which under the outer periphery of said rotating body inlet holes for the additional air are provided, an adjusting ring operated from the ascending rotating body for closing or opening said inlet holes, means for connecting said adjusting ring with the axle of the rotating body so that said ring is lifted off said air inlets according to the movement of the rotating body, and a throttling element in the suction pipe connected with said axle of the rotating body for regulating the inflow of explosive mixture.

3. A rotating air inlet and gas mixture regulator for internal combustion engines comprising in combination with a rotating body raised by the suction draft of the motor against the action of a spring, a casting having an enlargement in the plane of the rotating body in which under the outer periphery of said rotating body inlet holes for the additional air are provided, an adjusting ring operated from the ascending rotating body for closing or opening said inlet holes, means for connecting said adjusting ring with the axle of the rotating body so that said ring is lifted off said air inlets according to the movement of the rotating body, a throttling ring in the suction pipe below said rotating body tapered towards the upper edge and a spherical throttling element in said throttling ring connected with the axle of said rotating body so that the passage for the inflow of the explosive mixture is regulated according to the position of the throttling element.

4. A rotating air inlet and gas mixture regulator for internal combustion engines comprising in combination with a rotating body raised by the suction draft of the

motor against the action of a spring, a casting having an enlargement in the plane of the rotating body in which under the outer periphery of said rotating body inlet holes 5 for the additional air are provided, and an adjusting ring operated from the ascending rotating body for closing or opening said inlet holes, an outer adjusting ring covering said air inlets, means for adjusting said 10 outer adjusting ring by hand and for secur-

ing the same in adjusted position and means for indicating the adjusted position of said outer adjusting ring.

In testimony whereof I affix my signature in presence of two witnesses.

KURT VOLZ.
